ONE MAN CAMPER BODY

Jim L. Douglas, Lakewood, Gary J. Hart, Denver, and
Norman J. Germaine, Littleton, Colo., assignors to
Super Sport Sleepers, Inc., Denver, Colo.

Filed Oct. 18, 1971, Ser. No. 190,432

Term of patent 14 years

Int. Cl. D12—16
U.S. Cl. D12—156

FIG. 1

FIG.2

FIG.3

FIG.4

FIG.5

FIG.6

FIG. 1 is a rear perspective view of a "one man camper body" showing our new design; FIG. 2 is a top plan view thereof;

FIG. 3 is a rear elevational view thereof;

FIG. 4 is a front elevational view thereof;

FIG. 5 is a right side elevational view thereof; and FIG. 6 is a sectional elevational view taken along line 6-6 of FIG. 3.

The left side is a mirror image of the right side shown in FIG. 5 and the bottom is plain.

We claim:

The ornamental design for a one man camper body, as shown and described.
